SHIFTABLE BED RAIL TABLE

Filed June 30, 1945

UNITED STATES PATENT OFFICE

2,452,160

SHIFTABLE BED RAIL TABLE

Roman L. Smith, Los Angeles, Calif.

Application June 30, 1945, Serial No. 602,543

4 Claims. (Cl. 311—26)

1

This invention is in the class of special furniture and consists especially of a portable table device for use on bedsteads.

It is an object of the invention to provide a simple, substantial, light weight, inexpensive, and readily portable table device involving constructional details which permit of the easy arrangement of the device, hereinafter called the table, upon the side rails of a conventional bed frame, and as easily dismounted.

It is a noticeable object of the invention to provide a temporary table that may be quickly and safely mounted on the bed rails and which involves features of construction which wholly eliminate any manner of alterations, injury and special work or additions on or to the bed as an essential in the case of the instant table.

A further object of the invention is to provide, in this table means for its ready adjustment to rails which may be different depths and of various cross-top widths as may frequently be found extensively in general use in homes and a great many different institutions.

Another distinctive object of the invention is to provide a bed table which snugly fits the bed rails against side play and at the same time is quite readily shiftable toward or from the head of a bed for comfortable use near to the hands of the occupant of the bed, or pushed away toward the foot of the bed when the table is not immediately in service. And in this connection it is an object of the invention to provide a table which while light and compact is, at the same time very commodious.

Further, an object of the invention is to provide a bed table whose top plane height may be readily adjusted as needed by different individual users. And relative to this, an object is to provide a table, which when dismounted from a bed may be easily collapsed into a compact position of its parts so that the folded table will take up but a very small floor area if stood on end in a closet or other storage room.

The invention consists in certain advancements in this art as set forth in the ensuing disclosure and having, with the above, additional objects and advantages as hereinafter developed, and whose construction, combinations, and details of means, and the manner of operation will be made manifest in the following description of the here-with illustrative embodiment; it being understood that modifications, variations and adaptations may be resorted to within the scope, spirit and principle of the invention as it is more particularly claimed in the addendum.

2

Figure 1 is a perspective of the installed table.

Figure 2 is a detail section showing arrangement of a foot roller device for a wide top bed rail.

Figure 3 is a face view of a leg element with open-end slot for ready adjustment of height of the table, as to a bed.

Figure 4 is a detail showing an underfolded leg in latched position.

The table incorporates a top 2 which may be of any desired stiff material and of any width and length, to suit immediate given cases of installation; as for wide or narrow beds; rails R of a narrow bed being here shown. At each end of the table is a bottom, cross cleat 3 set slightly back from its end of the top 2. Hinged to the bottoms of these cleats are end table leg frames 4 and 5, and being duplicates, description of one will suffice for both.

Each frame involves a pair of short, coplanar, flat leg planks 6—6 rigidly fixed in parallel position as by cross-braces 7, and near the upper ends of these legs are the hinges 8 foldably affixing the frames to the said cleats; wherefore to permit of these frames being folded flat, close up to the bottom of the table top 2, and will thus take up small floor space when the collapsed table is stood on end in any convenient room or closet.

One leg of each pair has a series of holes 10 and the other leg has a slot 11 opening to the foot 30 of the leg, as in Fig. 3; and in the assembled table the holes in one leg are diagonally opposite to the holes in the other pair of legs, and so are the said slots, whereby to effect stability of the mounted table.

The lower ends of the legs (of each pair) are adapted to readily slide into place between upstanding cheek parts or plates 12—13 laterally spaced by and rigidly affixed to a bottom, frame cross bar 14, which is of about the same thickness as the leg planks. Passing through the upper ends of the two pairs of cheeks, are respective bolts 15, 17 piercing the holes or slots in the leg planks, as the diagonal arrangement justifies; thereby permitting the easy vertical adjustment 45 of the legs in the cheek spaces to bring the table top to a desired height above the rails R, and over the bed occupant. The diagonal disposition of the bolt holes 10 provides for stability whilst the bolts in the slots 11 are being tightened.

Means are provided which not only rigidly affix the cheeks to the bar 14 but at the same time form a runner device slidably mounting the made up table on the bed rails. This means includes a stiff axle bolt 16 whose outer end pierces a respective pair of cheeks 12—13 and the interposed

bar 14 and whose enlarged body part 18 relatively receives one or more running rollers 19 which track on the top edges or faces of the given rails R.

There is preferably a pair of these bolts 16 for each pair of cheeks at the ends of the respective bar 14 and on the inner ends of each pair is fixed an inner plate 20 covering the near ends of the interposed rollers 19 and hanging down along the inner sides of the bed rails R, whilst the adjacent rail cheek lies near the opposite side of the near rail R. Since the depth of the rails may vary the cheeks and the interposed portions of the bar 14 may have a plurality of sets of holes, as 21, to enable the respective pair of rollers to set higher or lower on the lower part of the leg frame.

If so desired suitable knuckle-joint link braces 22 may be connected to the leg frames and to the near ends of the table top 2 to brace the frames in open, bed mounted position.

After the table has been properly adjusted and mounted on the given bed rails the table can be shifted along the rails to desired position—for use or non-use.

Felt, or other facings 23 may be fixed to the leg cheek and the inside plate which straddle the rails so that the finish surface thereof will not be marred, and the rollers also may be of a protective and noiseless character, in whole or in feature.

When the leg frames are infolded under the top 2 as shown in Fig. 4 they are thus latched by a simple, appropriate spring or other latch 25.

What is claimed is:

1. A bed table including a top element to be transversely mounted over a bed, pairs of coplanar, spaced and rigidly connected leg parts and which pairs are hingedly connected at their upper ends to the ends of said element to be folded inwardly thereunder when not in table use, foldable, stabilizing braces connecting said

element and the leg parts, means to fasten the leg parts in infolded position to the said element, and a pair of bed rail trucks including upright pairs of spaced socket plates between which the lower ends of respective leg parts are adjustably slideable and each truck including a side bar on the ends of which respective pairs of socket plates are fixed, clamp bolts in the upper ends of pairs of plates and which pass through the interposed leg parts and operate to clamp said plates thereon, axle bolts passing through the truck plates, and bed rail rollers mounted on the inner ends of the axle bolts.

2. The table of claim 1; and inside, guide plates on the inner ends of the rollers axles.

3. The table of claim 1; a diagonal pair of the leg parts having vertical rows of holes for the clamp bolts and the other diagonal pair of leg parts having elongate slots for respective clamp bolts.

4. The table of claim 1; the socket plates having upper and lower sets of holes for selective insertion of the axles bolts to change elevation of the plates as to the bed rail for change of horizontal plane of the table element.
